UNITED STATES PATENT OFFICE

FREDERICK J. ENNIS, OF PALMYRA, NEW JERSEY

AEROPLANE-ASCENSION APPARATUS

Application filed December 15, 1926. Serial No. 154,894.

This invention relates to aeroplanes or ships of the heavier-than-air type adapted to be propelled through the air, and particularly to means for producing flight in a vertical direction.

The apparatus is designed for use in connection with ships of heavier than air type and the invention relates to means for producing flight in a vertical direction.

10 Aeroplanes now require a considerable runaway space on land or water in which to gain sufficient momentum to enable them to rise, and also require a considerable level area to enable them to land with safety.

15 The objects of my invention are to provide means whereby an air ship may take off from or land with safety upon an open space of comparatively limited area such as a small city lot, the roof of a building, the deck of 20 a ship, or a small body of water, and to provide means whereby, if the motor of the ship fails to function or to function efficiently, the speed of descent of the ship may be controlled and a gentle landing made.

25 These objects and other advantages I attain in the manner hereinafter described, reference being had to the accompanying drawings in which

Figure 1 is a representation of a device constructed in accordance with my invention and adapted to operate with a power plant not shown.

Figure 2 shows the device applied to a plane of the heavier-than-air type.

35 Figure 3 is a drawing showing an analysis of the forces operating upon my device when it is rotated by a suitable power plant, and how a rotating movement of the device will produce a vertical torque sufficient to enable 40 the device to ascend against gravity.

Considering Figure 1, numeral 5 represents my device which may be called a conduvane since it consists essentially of a frusto-conical body 6, attached to a power driven shaft and having vanes 7 and 8. The frusto-conical body may be a complete cone but I have shown it as of frusto-conical form which permits attachment of the apex to the driving shaft, and will describe it as a frusto cone. The vanes have one edge tangentially

affixed to opposing elements of the frusto-cone, and the other edge in the plane of the portion 9 of the cone. An analysis of vane 7 shows that portion A B of edge B C, that is not tangentially secured to the surface, is 55 the same length as an element of the cone, for example A D. In other words, the length of the bottom side of the vane extends beyond the base diameter parallel thereto, a distance equal to the side of the vane tangentially secured to the cone, or C E. C E obviously is equal to any element of the cone as A D. B C, however, may be of any length, and for various power plants will assume 60 corresponding suitable dimensions. The 65 vanes in Figure 1 are flat, although to reduce resistance, as may be desirable with different power plants, they may be curved to any suitable degree. Applicant limits himself to no form of construction or dimensions 70 of the vanes in combination with the frusto-cone. In theory, a true cone utilized with vanes substantially in the form of quarter circles of a circular plane shows to best advantage. In practice, a hollow frusto-cone 75 is employed. An expedient such as cover 10 may be employed to reduce resistance if the device is used in a position where great friction would be encountered against the interior of the cone. Shaft 11 may be coupled 80 to the cone in any suitable manner to connect with a power plant to supply a rotary movement to the conduvane.

Figure 2 shows a conduvane suitably mounted on an aeroplane. To reduce air resistance against the cover, the device may be mounted beneath the machine if coupled through a bearing that will protect the power plant against the upward thrust of the conduvane.

Upon rotating the conduvane clockwise a lifting movement illustrated in Figure 3 is produced. Each vane when revolving tends to create a vacuum between its inner surface 95 and the outer side of the conical portion. The surrounding air will immediately rush in. The action is comparable to that resulting from a sudden opening of a door, where the plane of the door quickly creates a partial 100

vacuum which is followed by a gust of wind rushing in to fill the void.

When the vanes cause a similar recurrent rushing in of air they set up a plurality of forces against the inclined outer surface of the frusto-conical body of the conduvane. The swing of each vane will set up a force against the outer conical surface measured by the length of the projecting side and designated as F G in Figure 3. Resolving resultant force F G against inclined side F H of the conduvane, force H J is represented as a vertical component and F G the horizontal component, in the directions indicated. The resistance of the air will set up counter forces resolved as K H horizontally and K F vertically in a direction opposed to the first forces. K F will cancel H J and K H cancel an equivalent component or F J of the horizontal component of original force F G. This leaves J G representing that portion of the force not canceled. Resolving J G against the inclined surface as shown, the horizontal component J G and vertical component G L, are the representations of the component forces, in the directions indicated. The same analysis is applicable to the other vanes. Since J G will cancel the horizontal force set up in an opposite direction by the oppositely disposed vane, the force represented by vertical component G L produced by each vane will alone remain. This force in the conduvane illustrated in Figure 3 would equal 2 G L. The force would lessen if the number of vanes were increased without regard to the size of the conduvane. Maximum results are obtained from the use of two vanes on the conical surface of a size sufficient to utilize full power of the motor without slip from too small a vane, or resistance from too large a vane or due to using too many vanes.

In Figure 2, the conduvane may be coupled to a clutch to the same motor used to drive the propeller, or by a separate power unit.

As the plane begins to move forward, the conduvane would commence to rotate at its maximum speed to impart an upward thrust to the machine, in aid of the propeller in combination with the elevator controls. If the forward propulsion means began to function unsatisfactorily when in the air, the conduvane will either serve as a brake or in conjunction with the disabled propeller means, effect a landing without precipitately crashing.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

I claim:—

1. A device adapted to be rotated by a power means, for supplying an upward movement to an aeroplane, consisting of a hollow frusto-cone, a plurality of vanes oppositely secured to the cone, each vane having its secured side equal in length to an element of the frusto-cone between its bases and a second side in a plane perpendicular to the secured side, the ends of said sides being joined by a third side in the form of a curve. 70

2. A frusto-conical body having its wall inclined upwardly and outwardly at an angle of approximately 45° to its base; quarter circular vanes tangentially secured thereto, 80 and means for imparting rotation to the body.

3. A frusto-conical body, a pair of quarter circular vanes tangentially secured to the outer wall thereof and extending in opposite directions, and means for imparting rotation to the body. 85

4. A frusto-conical body, quarter circular vanes tangentially secured to the outer wall thereof, and means for imparting rotation to the body, whereby sufficient forces are set up by said vanes to raise the body. 90

5. A frusto-conical body; a pair of quarter circular vanes tangentially secured to the outer wall thereof, the vanes being disposed opposite each other and extending in opposite directions in parallel planes, and means for imparting rotation to the body. 95

6. A frusto-conical body; a pair of oppositely disposed quarter circular vanes tangentially secured to the outer wall thereof, one of the straight edges of the vanes extending substantially from bottom to top of the body, and means for imparting rotation to the body. 100

7. A frusto-conical body; a pair of oppositely disposed quarter circular vanes tangentially secured to the outer wall thereof, one of the straight edges of the vanes extending substantially from bottom to top of the body and the other straight edge extending in a plane perpendicular to the axis of the frusto-conical body, and means for imparting rotation to the body. 105

8. Means for imparting vertical flight to a heavier than air machine, including a hollow frusto-conical body having its wall inclined upwardly and outwardly at an angle of approximately 45° to its axis, substantially quarter circular vanes having a straight side of each attached to the body at opposite sides thereof with the vanes extending tangentially in opposite directions, the other straight sides of the vanes being disposed in the plane of the small end of the body and on parallel lines, and a shaft secured to the body. 110

9. A propeller comprising a frusto-conical body, vanes secured to the sides of the cone, and means to rotate the organization 115

tending to move it with the base of the cone in advance.

10. A propeller comprising a frustro-conical body having its side walls arranged at an angle of approximately 45° to its axis, vanes secured to the sides of the cone, and means to rotate the organization tending to move it with the base of the cone in advance.

10. A propeller comprising a frustro-conical body, spirally inclined vanes secured to the sides of the cone and means to rotate the organization tending to move it with the base of the cone in advance.

12. A propeller comprising a frustro-conical body, vanes secured to the sides of the cone and extending spirally to a greater radial distance than the radius of the base, and means to rotate the organization tending to move it with the base of the cone in advance.

20. 13. A propeller comprising a frustro-conical body having a base coinciding with the plane of a spherical segment, vanes secured to the sides of the cone, and means to rotate the organization tending to move it with the base of the cone in advance.

25. 14. A propeller comprising a frustro-conical body having a base coinciding with the plane of a spherical segment, vanes secured to the sides of the cone and extending spirally to a greater radial distance than the radius of the base, and means to rotate the organization tending to move it with the base of the cone in advance.

30. 15. A propeller comprising a frustro-conical body having its side walls arranged at an angle of approximately 45° to its axis and a base coinciding with the plane of a spherical segment, vanes secured to the sides of the cone and extending spirally to a greater radial distance than the radius of the base, and means to rotate the organization tending to move it with the base of the cone in advance.

45. In testimony whereof I have signed my name to this specification.

FREDERICK J. ENNIS.
